UNITED STATES PATENT OFFICE.

WILLIAM H. RIPLEY, OF ORANGE, NEW JERSEY, ASSIGNOR TO THE PROMETHEUS ELECTRIC COMPANY, A CORPORATION OF NEW YORK.

ELECTRIC SWITCH.

1,299,617.

Specification of Letters Patent.

Patented Apr. 8, 1919.

Application filed April 9, 1917. Serial No. 160,829.

To all whom it may concern:

Be it known that I, WILLIAM H. RIPLEY, a citizen of the United States, residing at the city of Orange, Essex county, in the 5 State of New Jersey, have invented certain new and useful Improvements in Electric Switches, of which the following is a full, clear, and exact specification.

This invention relates to improvements 10 in electric switches, and more particularly to switches of the type in which arcing of the current is prevented upon the opening of the switch by a sudden, quick movement of one of the contacts of the switch relatively to 15 the other thereof.

One of the features of the invention is to provide a switch of this character which will be positive in its operation.

Another feature is to provide a switch 20 which is not liable to get out of order.

Another feature is to provide a switch which is comparatively simple in construction and inexpensive to manufacture.

Other objects will in part be obvious and 25 in part be pointed out hereinafter.

To the attainment of the aforesaid objects and ends my invention consists in the novel details of construction, and in the combination, connection and arrangement 30 of parts hereinafter more fully described and then pointed out in the claims.

In the accompanying drawings showing 35 an illustrative embodiment of the switch, and in which the switch is shown in its open position,

Figure 1 is a front view of a sterilizer having the improved switch affixed thereto;

Fig. 2 is a plan view of the switch;

Fig. 3 is a sectional view taken substantially on the line 3—3 of Fig. 2;

Fig. 4 is a sectional view taken substantially on the line 4—4 of Fig. 2;

Fig. 5 is a sectional view taken substantially on the line 5—5 of Fig. 2, and

Fig. 6 is a view showing the switch parts in separated relation.

Referring to Fig. 1 of the drawing 10 represents an electrically heated sterilizer of any suitable type having secured to one of its walls the improved switch 11 which forms the subject matter of the invention, and which is adapted to open automatically when the liquid within the sterilizer has evaporated, in order to prevent the appa-

ratus becoming overheated or burned out. 55 While, for purposes of illustration, the switch 11 is shown in connection with a sterilizer, it is, of course, to be understood that it may be employed in connection with any other type of electrical apparatus requiring in its operation the use of a switch 60 of this character.

Referring to Figs. 2 to 5, inclusive, 12 indicates a frame provided with a face plate 13, preferably formed of insulating material 65 and supporting two pairs of spaced contacts 14, 14, the free ends 15 of which extend through the face plate 13. One of the contacts of each pair is connected to one of the terminals of the electric heater of the 70 sterilizer and the other contact is connected to one of the terminals of a suitable source of electric current.

Rotatably supported by the frame 12 is a shaft 16 having an arm 17 secured to one 75 end thereof by means of which the shaft may be rotated. Rotation of the shaft 16 in one direction is automatically effected by means of a spring 18 coiled about the shaft 16 and having one of its ends engaging the frame 12 and its other end engaging the arm 17. Rotary movement of the shaft 16 in either direction is limited by means of a member 19 secured to the shaft 16 and provided with shoulders 20, 21 adapted to engage 80 a pin 22 carried by the frame 12.

Loosely mounted upon the shaft 16 is a yoke-shaped support 23 carrying a pair of contacts 24, 24 adapted to co-act with the free ends 15 of the pairs of contacts 14, 14, 90 to control the flow of current from the source of electric energy to the heater. Secured to one end of the yoke 23 is a member 25 provided with projections 26 and 27 and with an intermediate projection 28. When 95 the switch is in its open or inoperative position the projection 26 of the member 25 engages a stop 29 secured to the frame 12.

Loosely mounted upon the shaft 16 and positioned alongside of the member 25 is 100 an elongated cam 30 having cam surfaces 31 and 32 adapted to be engaged by the free end of a spring 33 secured to the frame 12. The cam surfaces 31, 32 meet and form 105 a point at one end of the cam 30, and at its other end the cam is provided with oppositely disposed, laterally-extending lugs 34, 35. When the switch is in its open position

the lug 35 of the cam 30 is in engagement with the projection 27 of the member 25, and the spring 33 is in engagement with the cam surface 31.

- 5 Secured to the shaft 16 is a cam actuating member 36 provided with two arms 37 and 38 one or the other of which is adapted to engage the lug 34 of the cam 30 when the shaft 16 is rotated, depending upon the direction of rotation of the shaft. The member 36, which is in engagement with the cam 30, together with the collar 39 secured to the shaft 16 and engaging the yoke 23 prevent longitudinal movement of the yoke 10 23 and the cam 30 relatively to the shaft 16. A spring 40 engaging the yoke 23 at one end thereof holds the same against rotary movement during the rotation of the shaft 16 until the yoke is positively rotated by 15 means of the cam 30, as hereinafter described.
- 20 The operation of the switch is as follows:—

When the switch is open the parts will 25 occupy the positions shown in the drawings. In order to close the switch the arm 17 is moved to cause the shaft 16 to rotate in a clockwise direction, as seen in Fig. 4, and in a counter-clockwise direction, as seen in 30 Fig. 5. Referring to Fig. 5, as the shaft 16 rotates the arm 37 of the cam actuating member 36 will come into engagement with the lug 34 of the cam 30 whereupon further rotation of the shaft 16 will cause the 35 cam 30 to rotate in unison therewith. As the cam 30 rotates the free end of the spring 33 will be depressed and placed under increased tension by the sliding engagement of the cam face 31 therewith until the 40 pointed end of the cam comes into engagement with the spring 33 at which instant the longitudinal axis of the cam 30 is perpendicular to the face of the spring. As the cam 30 continues to rotate the pointed end thereof will move out of engagement with the spring 33 and as soon as the longitudinal axis of the cam passes beyond its perpendicular position with respect to the face of the spring 33 the latter is free to spring 45 back to its normal position. As the spring returns to normal position it will, by its co-action with the cam face 32, cause a quick rotation of the cam 30 about the shaft 16 until the cam face 32 engages the free end of the spring 33 throughout substantially the entire length thereof whereupon the rotation of the cam 30 will be arrested. During this quick rotation of the cam 30 the lug 35 thereof, which will have come into 50 engagement with the projection 28 on the member 25, will cause a quick rotation about the shaft 16 of the member 25 and therefore of the yoke 23 secured thereto and carrying the contacts 24, whereby the contacts 24 will be quickly and forcibly moved 55 into engagement with the free ends 15 of the pairs of contacts 14, 14 thereby closing the switch.

When the shaft 16 is rotated in the reverse direction to open the switch a similar result is obtained, the parts, of course, moving in a direction opposite to that above described. As the shaft 16 rotates in the reverse direction the arm 38 of the cam actuating member 36 will engage the lug 34 70 of the cam 30 thereby causing the cam to rotate in unison therewith and to depress the spring 33 until the lug 35 of the cam engages the projection 27 of the member 25 secured to the yoke 23. At substantially the 75 same time that the lug 35 engages the projection 27 the longitudinal axis of the cam 30 will pass beyond its perpendicular position with respect to the face of the spring 33 as a result of which the spring will return to its normal position, and during the 80 return movement of the spring a quick rotary movement of the cam 30 and yoke 23 relatively to the shaft 16 will take place, in a manner similar to that above described 85 with respect to the closing of the switch. By reason of the quick rotary movement of the yoke 23 the contacts 24 carried thereby will be moved quickly out of engagement with the free ends 15 of the pairs of contacts 90 14, 14 thereby causing a quick break of the current and insuring that no arcing will occur between the coacting contacts as the 95 switch is opened.

In use in connection with a sterilizer, as shown for purposes of illustration in Fig. 1, the switch is closed by manually raising the arm 17 which is held in its raised position by means of a suitable fusible member 100 41 supported upon the sterilizer. Should the liquid within the sterilizer completely evaporate the temperature will rise and cause the member 41 to fuse, thereby permitting the spring 18 to rotate the shaft 16 105 to open the switch in the manner above described.

Having thus described my said invention what I claim and desire to secure by Letters Patent is:—

1. An electric switch comprising a frame, 110 contacts supported thereon, a shaft rotatably mounted on said frame, a contact rotatably supported upon said shaft, and means carried by said shaft to move said contact into and out of engagement with said contacts 115 when said shaft is rotated, said means comprising a member rotatable with respect to said shaft and to said contact, substantially as specified.
2. An electric switch comprising a frame, 120 contacts supported thereon, a shaft rotatably mounted on said frame, a contact rotatably supported upon said shaft, an actuating member rotatably mounted upon 125 said shaft and free to move with respect to 130

said contact, means operatively connected to said contact and adapted to be engaged by said actuating member to move said contact into and out of engagement with said contacts, and means to actuate said actuating member, substantially as specified.

3. An electric switch comprising a frame, contacts supported thereon, a shaft rotatably mounted on said frame, a contact 10 rotatably supported upon said shaft, an actuating member movably mounted upon said shaft and free to move with respect to said contact, means carried by said shaft to move said actuating member for a portion of its movement as said shaft is rotated, and means to move said actuating member for the remainder of its movement independently of said shaft, said actuating member serving to move said contact into and out of 20 engagement with said contacts during its movement independent of said shaft, substantially as specified.

4. An electric switch comprising a frame, contacts supported thereon, a shaft rotatably mounted on said frame, a contact 25 rotatably supported upon said shaft, an actuating member movably mounted upon said shaft and free to move with respect to said contact, means carried by said shaft to move said actuating member for a portion of its movement as said shaft is rotated, means to move said actuating member for the remainder of its movement independently of said shaft, and means operatively 30 connected to said contact and adapted to be engaged by said actuating member during its movement independent of said shaft to move said contact into and out of engagement with said contacts, substantially as 35 specified.

5. An electric switch comprising a frame, contacts supported thereon, a shaft rotatably mounted on said frame, a contact 40 rotatably supported upon said shaft, an actuating member rotatably mounted upon said shaft and free to rotate with respect to said contact, means carried by said shaft to rotate said actuating member for a portion of its movement as said shaft is rotated, means to rotate said actuating member for the remainder of its movement independently of said shaft, and means operatively 45

connected to said contact and adapted to be engaged by said actuating member during its movement independent of said shaft to move said contact into and out of engagement with said contacts, substantially as 55 specified.

6. An electric switch comprising a frame, contacts supported thereon, a shaft rotatably mounted on said frame, a support 60 rotatably mounted on said shaft and carrying a contact, a member carried by said support and provided with projections, a member rotatably mounted upon said shaft 65 and having a lug adapted to engage either one of said projections, means secured to said shaft to rotate said rotatable member to cause said lug to engage either one of said projections, and means effective after 70 said lug has engaged either one of said projections to rotate said rotatable member about said shaft whereby said support will be rotated about said shaft to move said contact into or out of engagement with said 75 contacts, substantially as specified.

7. An electric switch comprising a frame, contacts supported thereon, a shaft rotatably mounted on said frame, a support 80 rotatably mounted on said shaft and carrying a contact, a member secured to said support and provided with projections, a cam rotatably mounted on said shaft and provided with a lug adapted to engage either one of said projections, said cam having two 85 cam faces, means secured to said shaft to rotate said cam to cause said lug to engage either one of said projections, and a spring co-acting with either one of said cam faces after said lug has engaged either one of 90 said projections to rotate said cam about said shaft, whereby said support will be rotated to move said contact into or out of engagement with said contacts, substantially 95 as specified.

Signed at the city of New York, in the county and State of New York, this 5th day of April, one thousand nine hundred and seventeen.

WILLIAM H. RIPLEY.
